COUNTER FIXTURE

Jacob Perry Smith, Canton, Ohio, assignor to Old
King Cole Incorporated, Canton, Ohio, a cor-
poration of Ohio

Application January 18, 1944, Serial No. 518,735

8 Claims. (Cl. 211—130)

The invention relates to fixtures for displaying merchandise upon the counters of stores and more particularly to an adjustable fixture adapted to form any one of a number of different stepped or sloping designs for displaying various kinds of merchandise.

It is customary in many department stores, chain stores and the like to build up the top of the counter with special fixtures for displaying various types of merchandise. There are about eight or ten standard counter fixtures more frequently used in such stores, and under present practice these fixtures are built up blocks or boxes, usually constructed by a carpenter, and there is usually a complete set of the various designs or fixtures for each counter or showcase, the fixtures being changed from time to time for displaying various kinds of merchandise.

When any one type of fixture is in use the remaining seven or more built up fixture blocks comprising the set must be stored. This involves not only considerable expense in building the built up blocks or boxes but requires a large amount of storage space and requires considerable time and expense in hunting for the particular type of fixture desired when a change is made. Furthermore these fixtures are usually dressed with paper before the merchandise is placed thereon and this requires a considerable amount of paper to cover the top and ends of each fixture.

Thus an object of the present invention is to provide an adjustable fixture which may be quickly and easily adjusted to assume any of the several forms of such fixtures now in use.

Another object is to provide such a fixture comprising a flexible apron and a plurality of interchangeable end members of various shapes to provide the various forms of fixtures desired.

A further object is the provision of an adjustable fixture of this character in which the apron comprises a plurality of slats of differential widths having beveled or mitered edges and secured to a piece of fabric, cloth or other flexible sheet material.

A still further object of the invention is to provide an adjustable counter fixture of the type referred to in which detachable connecting means is provided upon opposite ends of certain of the slats of the apron for cooperation with means upon the end members.

Still another object is the provision of an adjustable fixture of the character referred to in which the flexible apron is so constructed that a convex or concave corner of at least a 90 degree

angle may be formed at the joint between any two of the slats throughout the entire length of the apron.

The above objects together with others which will be apparent from the drawings and following description of a preferred embodiment of the invention, or which may be later referred to, may be attained by constructing the adjustable counter fixture in the manner illustrated in the accompanying drawings, in which

Fig. 1 is a perspective view of the adjustable counter fixture to which the invention pertains, showing the same adjusted to form a triple stepped fixture;

Fig. 2 a similar view showing the device adjusted to form a double stepped fixture;

Fig. 3 a similar view showing a single step or block adjustment of medium height;

Fig. 4 a similar view showing a high, single step, or block;

Fig. 5 a similar view showing the fixture adjusted to form a low, flat table or platform;

Fig. 6 shows another double step adjustment;

Fig. 7 a similar view showing the fixture adjusted to provide a horizontal surface and an adjoining inclined surface;

Fig. 8 a detached perspective view of one of the end pieces as provided for producing the form of fixture shown in Fig. 1;

Fig. 9 a perspective view of another adjustment of the device somewhat similar to that shown in Fig. 7;

Fig. 10 a transverse sectional view through the flexible apron;

Fig. 11 a perspective view of the form of fixture shown in Fig. 7 with one end member removed;

Fig. 12 a transverse sectional view through the form of the fixture shown in Fig. 1;

Fig. 13 a transverse sectional view through the form of the fixture shown in Fig. 2;

Fig. 14 a transverse section through the form of the fixture shown in Fig. 3;

Fig. 15 a transverse section through the form of the fixture shown in Fig. 4;

Fig. 16 a transverse section through the form of the fixture shown in Fig. 5;

Fig. 17 a transverse section through the form of the fixture shown in Fig. 6;

Fig. 18 a perspective view of the form of the fixture shown in Fig. 9 with one end member removed;

Fig. 19 a section taken as on the line 19—19, Fig. 12;

Fig. 20 a fragmentary top plan view of one

corner of the assembled fixture with parts broken away for the purpose of illustration, and

Fig. 21 a bottom view of the flexible apron.

Referring now to the drawings in which similar numerals refer to similar parts throughout, the invention comprises generally the main framing element, in the form of a flexible apron, indicated generally at 25, and a plurality of pairs of end members indicated generally at 26 to 33 respectively, shaped to conform to eight different contours to which the flexible apron may be folded as shown in Figs. 1 to 7 inclusive and Fig. 9.

The flexible apron comprises generally a plurality of slats of differential widths, hingedly connected together at their adjoining edges so that the apron may be folded at any joint to produce a variety of contours. These slats may be formed of wood, plywood, corrugated cardboard or other rigid material and their edges are beveled, as at B, so that the apron may be easily folded at the joints between slats.

It should be understood that the number and arrangement of these slats may vary in fixtures designed for use upon counters of various widths. For the particular width of counter for which the fixture illustrated is designed, the flexible apron is shown provided with a relatively wide slat 34 at one edge and a relatively narrow slat 35 at the opposite edge, with intervening narrow and wide slats, 36 and 37 respectively, arranged in the manner shown in the drawings.

For the purpose of flexibly connecting the slats together at their adjoining edges all of the slats may be attached by cement or the like, to the underside of a flexible sheet 38, which may be formed of fabric, cloth, oilcloth or the like. The edges of the fabric sheet preferably cover the outer edges of the undressed slats 34 and 35, as indicated at 39 and 40 respectively.

Each of the end members comprises an outer sheet 41, of any suitable rigid material, such as pressed fibre, wood, plywood, metal or the like, having one or more blocks 42 of wood, or other suitable material, attached to its inner face, forming shoulders 43 spaced from the outer edges of the sheet 41 a distance equal to the thickness of the slats of the apron, so that when the apron is folded to any one of the eight different contours shown in the drawings, the corresponding end members may be attached to opposite ends of the folded apron, the slats resting upon the shoulders 43 of the end members and the outer edges of the sheets 41 being flush with the outer surface of the apron.

For the purpose of detachably connecting the end members to the apron, tongues 44 may be provided upon the blocks 42 of the end pieces for engagement in the keepers 45 fixed upon the end portions of certain of the slats.

The fixture may be quickly and easily adjusted to any of the several shapes illustrated by folding the flexible apron to the desired contour and attaching the proper end members thereto. For instance, in order to produce the triple stepped shape shown in Fig. 1, the apron is folded in the manner shown in Fig. 12.

The wide end slat 34 and the adjoining narrow slat 36 form the back of this shape of the fixture, the apron being then folded so that the upper step is formed by a narrow slat 36 and an adjoining wide slat 37, the riser for said step being formed by a narrow slat.

The next step of the fixture is formed by the next wide slat 37 and narrow slat 36 and the riser

thereof by the next adjoining narrow slat, while the lower step is formed of a narrow slat 36 and wide slat 37, and the narrow end slat 35 from the riser for said lower step.

5 The end members 26 are then inserted into opposite ends of the folded apron, the shoulders 43 of the blocks 42, on the inner faces of the end members, supporting the end portions of the slats in the adjusted position, and the fastening means 44-45 detachably connecting the end members to the folded apron.

To form the double stepped shape shown in Fig. 2, the apron is folded as shown in Fig. 13. The back of the fixture is formed by the wide end slat 34, the upper step by the adjoining pair of narrow slats 36 and wide slat 37, the next narrow slat 36 forming the riser for said upper step, while the lower step is formed by the next wide slat 37 and two narrow slats 36, the next 20 narrow slat 36 forming the riser for the lower step, and the remainder of the apron is folded back beneath the blocks 42 of the end members 27, which are attached as above described.

It will be seen that in forming some of the 25 other shapes, as shown in Figs. 3 to 6 inclusive, one or both ends of the flexible apron may be folded back beneath the blocks on the end members, as shown in Figs. 14 to 17 inclusive.

With this construction, it will be seen that a 30 great variety of shapes may be produced with a single flexible apron and pairs of end members conforming to the several contours to which the apron may be folded. When any particular shape of fixture is in use upon the counter, it is 35 only necessary to store the end members of the other shapes, thus requiring a relatively small storage space since these end members are relatively small in size as compared with the entire built up counter fixtures now in common use.

40 Furthermore, the outer surface of the end members may be finished in any desired manner so as not to require covering with the paper trim ordinarily used upon such fixtures, while the top of the fixture may be easily covered with paper 45 which may be cut from a roll and does not require special cutouts to cover the ends as is necessary under present practice.

When it is necessary to change the type of 50 counter fixture in order to display various kinds of merchandise, the fixture may be quickly and easily disassembled by removing the end members and folding the flexible apron to the desired contour and attaching the proper end members thereto.

55 I claim:

1. An adjustable counter fixture comprising an apron formed of a flexible sheet and a plurality of juxtaposed slats attached to the flexible sheet, the edges of the slats being beveled so that the apron may be folded to form a corner at any joint throughout its width, end pieces at opposite ends of the apron and cooperating means upon the end pieces and certain of the slats for detachably connecting the end pieces to the apron.

60 2. An adjustable counter fixture comprising an apron formed of a flexible sheet and a plurality of juxtaposed slats of differential widths attached to the flexible sheet, the edges of the slats being beveled so that the apron may be folded to form 65 a corner at any joint throughout its width, end pieces at opposite ends of the apron and cooperating means upon the end pieces and certain of the slats for detachably connecting the end pieces to the apron.

3. An adjustable counter fixture comprising an apron formed of a plurality of juxtaposed slats, means for flexibly connecting the slats together at their adjoining edges so that the apron may be folded to form a corner at any joint throughout its width so as to produce any one of a number of contours, end pieces shaped to conform to the contour to which the apron is folded, and means for detachably connecting the end pieces to the apron.

4. An adjustable counter fixture comprising an apron formed of a plurality of juxtaposed slats of differential widths, means for flexibly connecting the slats together at their adjoining edges so that the apron may be folded to form a corner at any joint throughout its width so as to produce any one of a number of contours, end pieces shaped to conform to the contour to which the apron is folded, and means for detachably connecting the end pieces to the apron.

5. An adjustable counter fixture comprising an apron formed of a plurality of juxtaposed slats, means flexibly connecting the slats together at their adjoining edges so that the apron may be folded to form a corner at any joint throughout its width so as to produce any one of a number of contours, end pieces shaped to conform to the contour to which the apron is folded, shoulders upon the inner surfaces of the end pieces spaced from the edges thereof a distance equal to the thickness of the slats and cooperating means upon the shoulders and upon certain of the slats for detachably connecting the end pieces to the apron.

6. An adjustable counter fixture comprising an apron formed of a plurality of juxtaposed slats of differential widths, means flexibly connecting the slats together at their adjoining edges so that the

apron may be folded to form a corner at any joint throughout its width so as to produce any one of a number of contours, end pieces shaped to conform to the contour to which the apron is folded, shoulders upon the inner surfaces of the end pieces spaced from the edges thereof a distance equal to the thickness of the slats and cooperating means upon the shoulders and upon certain of the slats for detachably connecting the end pieces to the apron.

7. An adjustable counter fixture comprising an apron formed of a flexible sheet and a plurality of juxtaposed slats attached to the flexible sheet, the edges of the slats being beveled so that the apron may be folded to form a corner at any joint throughout its width, end pieces shaped to conform to the contour to which the apron is folded, shoulders upon the inner faces of the end pieces spaced from the edges thereof a distance equal to the thickness of the slats and cooperating means upon said shoulders and upon certain of the slats for detachably connecting the end pieces to the apron.

8. An adjustable counter fixture comprising an apron formed of a flexible sheet and a plurality of juxtaposed slats of differential widths attached to the flexible sheet, the edges of the slats being beveled so that the apron may be folded to form a corner at any joint throughout its width, end pieces shaped to conform to the contour to which the apron is folded, shoulders upon the inner faces of the end pieces spaced from the edges thereof a distance equal to the thickness of the slats and cooperating means upon said shoulders and upon certain of the slats for detachably connecting the end pieces to the apron.

JACOB PERRY SMITH.
